James Chesters of Cumberland, C3 of Providence St. of Rhode-
Island & Providence Plantations

Letters Patent

The schedule referred to in these Letters Patent and making part
of the same, containing a description of the said James Chesters him-
self, of his improvement in the manufacturing of Cotton roping &
spinning of cotton Yarn &c

To all to whom these presents may come

Be it known, that I. James Chesters of Cumberland in the county
of Providence & State of Rhode Island & Providence Plantations have
invented a new and useful improvement, in the manufacturing of
cotton roping and spinning of cotton yarn, and that the following
is a full and exact description of the construction & operation of
said machine as improved by me

N°. 1. is the tube where the roping enters first from the rollers
2. is the traverse motion. N°. 3. right and left handed
screw. 4. Tinter which plays within apertures of the screw. 5. Spindle
that goes thro' the bobbin. 6. Roller that turns the bobbin. 7, 8
Pair of bevel gears that convey motion to the roller. 9. a frame
that is a bearing for all that is above described & revolves by means
of pulley N°. 10. to twist the roping. N°. 11. driving pulley for N^o.
12. N°. 13. Loose pulley to regulate the tightness of the band that
plays over pulleys N°. 11. 12. 13. 14. Spindles & pulley that give motion
to all inside the frame on flyer. 15. 16. 17. A shaft & two driving
pulleys to drive the spindles in the machine. Any number of
spindles can be put in a machine. 18. a revolving case to avoid
the imperfection of revolving in the air for the purpose of saving
power. The machine above described is called a double re-
volving speeder. I ask for Letters Patent to be granted, founded
upon the application to the machine of the loose pulley N°. 13. which
regulates the tightness of the band that plays over pulleys 11. 12. 13.
also of the application to the above machine of the right and left
handed screw N°. 3. and the revolving case N°. 18. which encloses the

machinery numbered as follows 2.3.4.5.6.7.8.9 - 11.12.13. the pulley
the right and left handed screw and the revolving case being necessary
to carry into effect the principle of the improvement -
